POLYMER COATED FABRIC

Howard L. Amberson, Madison, Wis., assignor to United States Rubber Company, New York, N.Y., a corporation of New Jersey

Filed Apr. 4, 1961, Ser. No. 64,615

Term of patent 14 years

(Cl. D87—3)

FIG. 1 is a plan view of a polymer coated fabric showing my new design; and

FIG. 2 is a sectional view of the polymer coated fabric of FIG. 1 along the line 2—2.

The dot and dash lines (other than the section line 2—2) on the drawing outline a design unit, which unit is repeated in regular succession, as indicated by the extensions beyond the unit boundaries.

I claim:

The ornamental design for a polymer coated fabric, as shown and described.
